UNITED STATES PATENT OFFICE.

ROBERT WEIR, OF CHICAGO, ILLINOIS.

LOG-ROLLER.

No. 845,152.

Specification of Letters Patent.

Patented Feb. 26, 1907.

Application filed July 25, 1903. Serial No. 167,058.

To all whom it may concern:

Be it known that I, ROBERT WEIR, a citizen of the United States of America, and a resident of Chicago, Cook county, Illinois, 5 have invented a certain new and useful Improvement in Log-Rollers, of which the following is a specification.

My invention relates to machines for transferring logs from a sawmill log-deck to the traveling carriage of a saw.

Generally stated, it is the object of my invention to provide a simplified and highly-efficient machine for delivering logs to the traveling carriage usually employed for presenting the logs to a saw.

A special object is to provide an arrangement whereby a comparatively slight incline to may be employed for delivering the logs to the carriage so as to avoid all danger of shock 15 and consequent breakage.

Another object is to provide a form of stop mechanism which will not only readily release the logs, but which after releasing a log cannot possibly become jammed or rendered 25 inoperative by the pressure of the pile of logs on the deck.

It is also an object to provide certain details and features of improvement tending to increase the general efficiency and service- 30 ability of a log-rolling machine of this character.

To the foregoing and other useful ends my invention consists in matters hereinafter set forth and claimed.

35 In the accompanying drawings, Figure 1 is a side elevation of a log-rolling machine constructed in accordance with the principles of my invention and showing also the saw-carriage which receives the logs from the deck,

40 whereon they are held by the stop mechanism. In this figure a log has been delivered to the saw-carriage and has been presented once or twice to the saw, as will be seen from its flattened appearance. Fig. 2 is a view

45 similar to Fig. 1, with the exception that in this figure the log shown on the carriage of the previous figure has been sawed up and disposed of and the stop mechanism is now being operated for the purpose of rolling a

50 fresh log onto the carriage. Fig. 3 is a plan of the log-rolling machinery and the saw-carriage shown in Fig. 1. Figs. 4 and 5 are respectively a side elevation and a rear elevation of the stop-arm shown in Figs. 1 and 2.

55 Fig. 6 is a sectional view on line 6-6 in Fig. 3.

As thus illustrated, my improved log-roll-

ing machine comprises an inclined log-deck A of any suitable form or construction. A shaft B is mounted in bearings on the said log-deck and is provided with a pair of stops 60 b. The said shaft is also provided with an arm b', adapted to connect with the pitman b². This pitman, as will be observed, is connected with the piston-rod of the steam-cylinder. The said piston operates to normally 65 hold the stops b in the position shown in Fig. 1. In this position it will be seen that the stops engage the first log on the deck and in this way cause all of the logs to remain stationary upon the deck A. The stop mechanism thus provided also involves a pair of levers or lifting-arms D, which are pivoted at d and provided at their other ends with segmental-shaped and downwardly-projecting arms d'. The lower ends of these arms d' are 70 provided with slots d'', adapted to receive the bolts d³, extending through the lower ends of the stops b. By referring to Figs. 4 and 5 it will be seen that the lower ends of said stops are preferably bifurcated, so as to receive the 75 slotted lower ends of the arms d'. In order to reduce friction, each bolt d³ is preferably provided with a sleeve d⁴, which works back and forth in the slot d''.

The saw-carriage E can be of any suitable, 80 known, or approved construction. For example, it can be arranged to travel on ways or rails e and can be provided with the usual head-blocks e'. The carriage thus constructed is arranged to travel into a position in 85 front of the log-deck, so that it may successively receive the logs held upon the latter. In Fig. 1 the log 2, as will be observed, has been delivered to the carriage and has 90 been presented to the saw, as will be seen 95 from its flattened outer side.

The operation of transferring the log from the deck to the carriage will be understood by referring to Fig. 2 and is as follows: After the log on the carriage has been sawed up 100 and disposed of the carriage is then moved into a position in front of the log-deck. Steam is now admitted below the piston in the cylinder C, and the upward pressure thus exerted upon the piston causes the pitman b² 105 to move the stops b and the levers D into the position shown in said Fig. 2. The operation of the stop mechanism in this manner involves, it will be seen, not only a removal of the stop from the path of the log 1, but 110 also a lifting of the levers D. The levers D when thus lifted provide an incline down

which the logs roll to the traveling saw-carriage. At the same time the rear segmental portions of the levers D are brought into position to engage the log 3, so as to prevent the logs remaining on the deck from following the log 1, which latter is the one to be delivered to the carriage. Thus the levers D not only successively lift and roll the logs upon the saw-carriage, but also hold the remaining logs against movement until the stops b are again brought into their normal or operative positions. At this juncture it will be seen that the thrust or pressure of the remaining logs upon the lever D is along a line which passes through the axis provided by the pivotal points d. In this way the pressure of the logs remaining on the inclined deck never have any tendency whatever to lift the levers D, thus allowing the piston and cylinder to readily pull the levers down and interpose the stops b in the path of the logs. This advantage is always present, it will be seen, regardless of the size of the log, for, as stated, the arms d' are segmental in shape and are radially formed relative to the axis about which the levers swing. In other words, the pressure of the logs on the deck will always be along a line passing through the axis upon which the levers swing regardless of the point at which the foremost log contacts with the curved surfaces of the lever-arms d'. Thus, as stated, the pressure of the logs can never tend to lift the arms D and can never make it in any wise difficult for the piston to draw the levers down into the position shown in Fig. 1. As another advantage of my novel form of stop it will be seen that the upper edges of the stop b recede or tilt toward the saw-carriage while the log is being raised by the levers D. In this way it is possible to deliver the logs to the saw-carriage with a very slight incline—that is to say, the incline necessary for rolling the logs is much less than it would be should the stops move directly downward. With this mode of operation the logs are delivered gently and without shock to the saw-carriage and without danger of breaking the head-blocks. In other words, with my improved construction the stop mechanism is not only of a character to preclude all possibility of its becoming jammed or rendered inoperative by the pressure of the logs, but is also nicely adapted to successively deliver the logs to the saw-carriage.

With further respect to the novel form of stop mechanism it will be seen that the stop-arms cannot give way or recede from the pressure of the logs, since any forward movement on their part is necessarily accompa-

nied by a lifting of the foremost log. In other words, the foremost log cannot roll forward and from the stop-arms, inasmuch as the weight of the log at such time is opposed to its forward pressure or momentum. Thus the dead-weight of each log is practically utilized for stopping it at the proper point on the deck and for preventing it from rolling from the stop-arms. For this reason my invention also contemplates a stop mechanism in which the weight of the log is employed for holding the stop-arms erect and in position to hold the log on the deck until the proper time for delivering it to the saw-carriage.

The stops b are adapted, it will be observed, to have a certain amount of movement relatively to the lifting members or levers D. This, as shown in the drawings, is accomplished by providing separate axes for the said stops and lifting-levers and providing swinging and preferably lost-motion connections between the stops and said levers. This construction insures a very effective and efficient operation of the log-roller, it being easily operated and controlled and at the same time sufficiently powerful and effective to cause the logs to be delivered one at a time in the usual and well-known manner. With the construction shown—that is to say, with the portions d' formed integral with the lifting-levers D—it will be seen that lost-motion connections consisting of the slots d² and the rollers d⁴ between the lifting-levers and the stops are desirable, as without these lost-motion connections there would not be sufficient relative movement between the lifting-levers and the stops.

What I claim as my invention is—

1. A log-rolling machine comprising a deck, a saw-carriage, a shaft carrying a stop-arm, a plurality of levers having their free ends directly but loosely connected to an arm on the stop-arm shaft and adapted to lift and roll the logs from the deck to the saw-carriage.

2. A log-rolling machine comprising a deck, a saw-carriage, a shaft carrying a stop-arm, a plurality of levers pivoted at their delivery end between the stop-arm and the saw-carriage and having their free ends directly but loosely connected to an arm on the stop-arm shaft adapted to lift and roll the logs from the deck to the saw-carriage.

Signed by me at Chicago, Cook county, Illinois, this 16th day of July, 1903.

ROBERT WEIR.
